CLAIM

The ornamental design for a high load display support system, as shown and described.

DESCRIPTION

FIG. 1 is a top perspective view of a high load display support system showing our new design.

FIG. 2 is a bottom perspective view of FIG. 1.

FIG. 3 is a front view of FIG. 1.

FIG. 4 is a rear view of FIG. 1.

FIG. 5 is a left-side view of FIG. 1.

FIG. 6 is a right-side view of FIG. 1.

FIG. 7 is a a to view of FIG. 1; and,

FIG. 8 is a bottom view of FIG. 1.

The broken lines shown on the drawings depict portions of the high load display support system that form no part of the claimed design.

1 Claim, 5 Drawing Sheets
